UNITED STATES PATENT OFFICE.

JULIUS BROWN, OF NEW YORK, N. Y.

INKING-ROLLER.

1,292,244.

Specification of Letters Patent. Patented Jan. 21, 1919.

Application filed October 4, 1918. Serial No. 256,847.

To all whom it may concern:

Be it known that I, JULIUS BROWN, a citizen of the United States, residing at New York, in the county of Bronx and State of New York, have invented certain new and useful Improvements in Inking-Rollers, of which the following is a full, clear, and exact specification.

This invention relates to inking rollers for printing presses or other suitable purposes, and has for its object to provide a stock spindle adapted to hold rollers of different lengths to suit various requirements.

The invention contemplates the provision of short metallic roller sections which may be placed on the stock spindle or removed therefrom to obtain the desired length of roller, the composition for the surface of the roller being molded upon said metallic sections. In this way the roller may be readily adjusted in length to correspond with the dimensions of the blocks of type to be inked, thus saving ink which would be wasted if the roller were too long.

Another object is to provide a roller with spaced sections of inking surface to fit blocks of type separated by blank spaces or margins, whereby ink is further conserved by not having idle portions of roller surface to be inked. Other objects will appear as the description proceeds.

The invention will be first hereinafter described in connection with the accompanying drawings, which constitute part of this specification, and then more specifically defined in the claims at the end of the description.

In the accompanying drawings, wherein similar reference characters are used to designate corresponding parts throughout the several views:—

Figure 1 is an elevation of a stock spindle having a plurality of metallic roller sections mounted thereon, showing how the roller appears before the inking surface is molded thereon.

Fig. 2 is an elevation, partly in section, of the same roller complete with the inking surface material molded thereon.

Fig. 3 is a section on the line III—III of Fig. 2.

Fig. 4 is a section on the line IV—IV of the same figure.

Fig. 5 is a sectional view of a roller made up of spaced surface sections, and

Fig. 6 is a diagrammatic view of spaced

blocks of type with which the sectional roller shown in Fig. 5 is designed to be used.

A roller of the desired length is designed to be built up on a stock spindle 1 which is formed with a longitudinal groove 2 in its surface from end to end to receive correspondingly shaped inwardly extending key lugs 3 on the metallic roller sections 4 of which five are illustrated in Figs. 1 and 2. It will be understood that these sections 4 may be made of any suitable length and that as many of them placed on the spindle as desired before molding the composite inking material 5 thereon as shown in Fig. 2. The outer surface of each of the sections 4 is roughened, as at 6, Figs. 1, 2 and 3, to retain the inking surface material 5 thereon.

Before the surface material is molded on the sections 4, they are locked together on the spindle by end collars 7 each of which has an inwardly extending key lug 8 and a set screw 9 adapted to engage the base of the longitudinal groove 2 for holding it in place. If a roller is found to be too long for a given piece of work, the surface composition 5 may be cut in line with any one of the meeting ends of the sections 4, and the sections thus separated may be removed from the spindle after the adjacent end collar has been taken off. The sections of the roller having the inking surface thereon, which are thus removed, may be stored away for future use, and when desired may be placed back on the spindle to lengthen the roller for other work. The end collar is, of course, put back on the spindle after each adjustment and clamped in place against the end of the roller sections remaining on said spindle.

Where the work to be inked consists of spaced blocks of type, as indicated at 10 in Fig. 6, the roller may be made up of spaced sections of inking surface to bridge the spaces or margins 11 between said blocks 100 of type. Such a roller is illustrated in Fig. 5 wherein the metallic sections 4 are spaced apart on the spindle 1 by a sleeve 12, and the inking surface material 5 is commensurate in length with said sections 4, leaving the space 13 between said surface sections corresponding to the margins 11 between the blocks of type to be inked. The length of the spacing sleeve 12 may, of course, be varied according to the width of the margins in the work, as may be the length of the surface sections of the roller to

correspond to the width of the blocks of type in each piece of work.

Having thus described my invention, what I claim as new and desire to secure by Letters Patent of the United States is:—

1. An inking roller comprising a spindle, a plurality of metallic roller sections detachably mounted so as to meet end to end on said spindle and forming a continuous cylindrical surface of constant diameter from end to end of said sections, and an inking surface of composite material molded directly on said sections and across the meeting ends thereof, whereby said inking surface material may be cut through in line

with any of said meeting ends of the sections for the purpose specified.

2. An inking roller comprising a spindle, a plurality of metallic roller sections fitted so as to meet end to end on said spindle and forming a continuous cylindrical surface of constant diameter from end to end of said sections, end collars on said spindle for detachably retaining the sections thereon, and a layer of composite inking material molded directly on said sections and across the meeting ends thereof for the purpose specified.

In testimony whereof I have signed my name to this specification.

JULIUS BROWN.
